UNITED STATES PATENT OFFICE.

MICHAEL GEARY, OF OIL CITY, PENNSYLVANIA; KATE GEARY, OF OIL CITY, PENNSYLVANIA, DANIEL O'DAY, OF NEW YORK, N. Y., AND JOSEPH SEEP, OF TITUSVILLE, PENNSYLVANIA, EXECUTORS OF SAID MICHAEL GEARY, DECEASED.

DESIGN FOR AN ENGINE-WHEEL.

SPECIFICATION forming part of Design No. 25,367, dated April 7, 1896.

Application filed May 11, 1895. Serial No. 549,003. Term of patent 14 years.

To all whom it may concern:

Be it known that I, MICHAEL GEARY, a citizen of the United States, residing at Oil City, in the county of Venango and State of Pennsylvania,

5 have invented and produced a new and original Design for Engine-Wheels, of which design the following is a specification.

In the accompanying drawings, Figure 1 is a view in elevation of an engine-wheel, showing my design; Fig. 2, a transverse section at the line $\alpha\alpha$ of Fig. 1; and Fig. 3, a section through the hub and counterbalance, these three views being deemed necessary to fully illustrate my design.

15 The leading feature of my design consists in a segmental counterbalance projecting from the hub of the wheel and two segmental flanges, each of the same radius as the counterbalance and projecting from the hub throughout that portion of the circumference thereof which is not occupied by the counterbalance, the outer or end surface of each flange being in the same plane as one of the corresponding surfaces of the counterbalance, 20 so that the wheel presents to the eye the appearance of having a continuous and unbroken annular portion surrounding its hub, the open spaces between the arms on the side of the axis opposite the counterbalance being

covered and concealed by the segmental flanges whose surfaces coincide both peripherally and endwise with like surfaces of the counterbalance.

30 Referring to the drawings, the engine-wheel is composed of a hub 1, arms 2, and a rim 3. A segmental counterbalance 4 projects from the hub on one side of the axis of the wheel, and two segmental flanges 5, each of the same radius as the counterbalance, project from the hub throughout that portion of its circumference which is not occupied by the counterbalance, the ends or outer surfaces of the flanges being in the same plane as and coinciding throughout, both peripherally and endwise, with those of the counterbalance. 35 The open spaces between the arms, adjacent to the hub, which are opposite the counterbalance, and which are indicated by the dotted lines in Fig. 1 and shown by the section, Fig. 2, are covered and concealed by the 40 flanges 5. 45

What I claim is—

The design for an engine-wheel substantially as herein shown and described.

MICHAEL GEARY.
